RETAINING CLIP

Emile P. Bolduc, Minneapolis, Minn., assignor of
one-half to Tip-Top Products Company,
Omaha, Nebr., a corporation of Nebraska

Application December 29, 1945, Serial No. 638,248

3 Claims. (Cl. 24—261)

1

This invention relates to fulcrumed clips particularly adapted to retain the curls or locks of human hair, but adapted for wide general use where it is desirable to, within a range of thicknesses, clamp and retain a series or multiplicity of individual elements.

It is an object of my invention to provide a simple and highly efficient spring clip of the fulcrumed jaw type which is adapted to be manufactured at low cost and constructed from a single piece of wire having an adequate degree of resiliency.

A further object is the provision of a simple, commercially economical method of making my improved clip from integral lengths of wire.

Another object is the provision of an ornate, compact, fulcrumed clip adapted to be readily manipulated to open a pair of cooperating clamping jaws and constructed to be disposed flush against a surface and to secure a multiplicity of plies, strands or other elements together in a pre-determined arrangement.

In beauty parlor work, the retaining of curls and waves is quite an essential feature. Adequate retention, easy application and comfort are factors in the success of retaining clips used upon human hair. My improved device complies with all requirements and is particularly well adapted for retaining curls and waves in beauty parlor culture.

These and other objects and advantages of my invention will be more apparent from the following description made in connection with the accompanying drawings wherein like reference characters refer to the same parts throughout the views and in which—

Fig. 1 is a perspective view showing a completed embodiment of my retaining clip in an opened position for receiving a curl or other material to be retained;

Fig. 2 is a perspective view with a portion of the length of wire broken away illustrating the first steps of bending utilized in the carrying out of my novel method;

Fig. 3 is a perspective view showing the carrying out of further steps;

Fig. 4 is a perspective view showing the completion of the essential steps of my method with the device in final form with the exception of crimping (if it is desired), one of the cooperating jaws;

Fig. 5 is a perspective view showing a completed device embodying another form of my invention with the jaws open for receiving material to be gripped;

2

Fig. 6 is a perspective view illustrating the first few steps of my method applied to the production of the second form;

Fig. 7 is a perspective view illustrating a number of subsequent steps;

Fig. 8 is a perspective view showing the device completed with the exception of crimping one of the jaws; and

Fig. 9 is a perspective view showing the application of my retaining clip for retaining curls formed in a woman's hair.

Referring now to the embodiment of my invention illustrated in Figs. 1 to 4 inclusive, my device is constructed from a single integral length of bendable but resilient material such as wire, constructed to form a pair of cooperating fulcrumed clamping jaws A and B which are normally disposed in closed clamping position and which are actuated for opening by a pair of actuating handles X and Y fixed to the inner and fulcrumed ends of jaws A and B respectively. Jaws A and B are in the form of elongated loops interconnected for resilient spreading by means of the short, looped actuating handles Y and X and are fulcrumed about a transverse leg or fulcrum element F which is intermediately connected with the two jaws and their actuating handles and serves as a part of the connection therebetween. One or both of the actuating handles X and Y are angled obtusely with respect to the general plane of the related jaws A and B to leave said handles X and Y divergent for actuation when the clip is in normal position.

The detailed structure, functions and advantages of my improved clip can best be understood by describing my novel method of manufacture or production, to wit:

A length of suitable wire or analogous material of a nature to retain its shape when sharply bent but nevertheless having a fair degree of resiliency, is selected. For the lighter clips used in curl retaining and for securing correspondence and light papers, ordinary piano wire has been found highly successful. For retaining and gripping files, heavier sheet material and for use as a clothes pin, heavier wire material possessing adequate resiliency, is recommended.

In carrying out my method, as illustrated in Figs. 1 to 4, the length of wire, preferably but not necessarily in straight form, is bent adjacent one extremity 11 into a substantially flat, U-shaped loop 12 constituting one of the jaws of the device. The loop shown is of rectangular form obtained through two bends of the stock at right angles although it will be understood that

this loop may be bent along an arcuate or variable curve. The very extremity 11 of the wire is bent to curve downwardly relative to the plane of loop 12 and this may be performed as the first step, simultaneously with the bending of the loop 12 or later in the production of my clip.

After formation of loop 12, the immediate stock of the wire adjacent the last leg formed, is bent upwardly at an obtuse angle to the plane of the adjoining leg and thereafter bent as shown, to form a squared loop 13 although it will be understood that the bends of loop 13 may be (but not preferably) formed by curved bending of the stock. The last leg 13a formed in loop 13 extends outwardly of the extremity 11 of the wire and the stock immediately adjacent thereto is rectangularly bent to traverse the inner end of the loop or jaw 12 and to underlie and engage the downwardly curved extremity, as shown in Fig. 3 and to lie behind the first leg formed on the actuator loop 13. This transverse length of wire 14 constitutes, in this form of the invention, the fulcrum element for the clip.

The stock immediate to transverse fulcrum element 14 is bent at right angles to the fulcrum, extending rearwardly from the loop of jaw 12 and at a divergent angle to the adjacent leg of the actuator loop 13, and said stock is thereafter bent into a square loop 15, preferably about similar in size and shape to the actuator loop 13. The second leg 16 formed in the making of actuator loop 15 (handle Y of the device) is extended beneath the transverse fulcrum element 14 as shown in Fig. 4 and it is then bent or doubled in the form of a V to extend in a plane substantially parallel with the plane of the loop 12 with its bent extremity extending, as shown, slightly beyond the extremity of loop 12 for abutment therewith to retain the jaws of the clip in opposed clamping relation for actuation to engage material to be clipped. From this description and inspection of Fig. 4, it will be seen that the last mentioned elongated loop forming the jaw B of my device, is also fulcrumed about the transverse element 14.

The carrying out of the several steps of my method as recited with angulation and bending of the various parts and legs of the device, to normally position the two jaws A and B into contact or abutment, provides for a strong torsional tension between the two jaws when the actuating handles X and Y are urged together, the jaws fulcruming upon the transverse element 14. In this connection, in the form disclosed, the upper jaw is mainly swung about the fulcrum 14 through the abutting relation of the angled portion at the forward side of the clip as viewed in Fig. 4, while the swinging movement of the lower jaw B is mainly occasioned through engagement of the underlying portion of the leg 16 in its relation to the fulcrum element. Torsional tension is built up of course, throughout the entire line of integral connection between the two jaws through fulcrum 14 and the co-operating actuating handles.

It is often desirable to crimp the clamping area of one of the jaws which is accomplished by applying crimping force preferably in a direction normal to the plane of the jaw.

The form of the clip and the essential steps of the method of manufacture as illustrated in Figs. 5 to 8 inclusive, are generally similar to the form disclosed first, although this second form is somewhat more expensive to manufacture.

In making this last mentioned form of my de-

vice, I again start with a length of suitable wire having requisite resiliency and ability to retain its shape when sharply bent. One extremity 21 of the length selected is inwardly bent, as shown in Fig. 6 and the stock adjacent thereto is then bent to form an elongated loop 22, as shown, of generally V-shape, said loop generally lying in a plane extending nearly coincident to the inturned extremity 24. The stock of wire immediately adjacent the second leg 22a of the loop formed is bent to form a fulcrum eye 23, preferably through a single convolution of the wire and the bight of the wire is then extended rearwardly and substantially longitudinally of the leg 22a and thereafter bent to form an actuating loop or handle 24. The second leg 24a of the handle 24 is then preferably, through a single convolution, shaped to form an eye 25 which surrounds the inwardly bent first mentioned extremity 21 of the wire, serving as a fulcrum element for the jaws. The immediate stock of the wire is then bent rearwardly at an acute angle to leg 24a, forming a leg 26a which extends in a common vertical plane with leg 24a, and the bight of the wire is thereafter bent into a U-shaped loop 26 preferably of similar shape and size to the actuator handle 24, the last formed leg of loop 26 extending to the first mentioned fulcrum eye 23, and the stock of wire immediately adjacent thereto being bent outwardly to pass through eye 23 and thereafter extended longitudinally and forwardly and bent into the form of an elongated loop 27, the last formed leg of which, 27a, extends rearwardly to the second fulcrum eye 25. The wire is then properly cut, or if the precise length is prepared before starting manufacture, the last extremity thereof is inturned at substantially right angles to the leg 27a and is also, with the first extremity 21 of the clip, passed through fulcrum eye 25. This normally leaves the two jaws or elongated loops 22 and 27 opposed in abutting relationship with the actuating handles or loops 24 and 26 angled for spreading of the jaws against torsional spring tension. In this form of the invention, fulcruming of both jaws takes place at both sides of the clip with the attendant torsional tensioning of the metallic spring wire throughout the connections including the bent portions of the actuating handles 24 and 26 with the immediate adjacent portion of the jaw legs and including also to some extent, the fulcrum eyes 23 and 25. As in the form of the invention previously described one of the jaws (as shown, 27) may be crimped to form humps or corrugations 27b, if desired.

In utilizing my device, it will be readily seen that quite a wide opening of the jaws may be easily obtained through finger pressure upon the two actuating handles. Thus, material having considerable variation in thicknesses may be readily accommodated between the jaws and the actuating pressure released to cause the jaws to tightly grip the material, plies, strands or the like. It will of course, be understood that various changes may be made in the form, details, arrangement and proportions of the various parts without departing from the scope of my invention.

In some uses of my improved clip, it is desirable to cover the stock of wire before bending of the parts with soft, tubular material such as rubber or fabric.

What I claim is:

1. A fulcrumed clip constructed from an integral length of resilient wire, comprising a first 75 U-shaped jaw member formed in an end portion

of said wire, a first actuating loop formed in the wire emanating from said first jaw member and extending rearwardly therefrom, a fulcrum element formed in the wire emanating from said first actuating loop and extending transversely across the base of said loop under the inner ends of said first jaw member, a second actuating loop formed in the wire emanating from said fulcrum element, said second actuating loop conforming generally in shape to said first actuating loop, but lying in a plane angulated acutely thereto, the wire extending from said second actuating loop under said fulcrum element and being formed into a second U-shaped jaw member normally lying in a plane parallel to and adjacent to the plane of said first jaw member, the end of said second jaw member extending over said fulcrum element.

2. A fulcrumed clip constructed from an integral length of resilient wire, comprising a first U-shaped jaw member formed in an end portion of said wire, a first actuating loop formed in the wire emanating from said first jaw member and extending rearwardly therefrom in a plane angulated obtusely to the plane of said first jaw member, a fulcrum element formed in the wire emanating from said first actuating loop and extending transversely across the base of said loop under the inner ends of said first jaw member, a second actuating loop formed in the wire emanating from said fulcrum element, said second actuating loop conforming generally in shape to said first actuating loop, but lying in a plane angulated acutely thereto, the wire extending from said second actuating loop under said fulcrum element and being formed into a second U-shaped jaw member normally lying in a plane parallel to and adjacent to the plane of said first jaw member, the end of said second jaw member extending over said fulcrum element.

3. A fulcrumed clip constructed from an integral length of resilient wire, comprising a first U-shaped jaw member formed in an end portion of said wire, the wire end being downwardly bent from the plane of said jaw, a first actuating loop formed in the wire emanating from said first jaw member and extending rearwardly therefrom in a plane angulated obtusely thereto, a fulcrum element formed in the wire emanating from said first actuating loop and extending transversely across the base of said loop under the inner ends of said first jaw member, a second actuating loop formed in the wire emanating from said fulcrum element, said second actuating loop conforming generally in shape to said first actuating loop but lying in a plane angulated acutely thereto, the wire extending from said second actuating loop under said fulcrum element and being formed into a second U-shaped jaw member normally lying in a plane parallel to and adjacent to the plane of said first jaw member, the end of said second jaw member being downwardly bent over said fulcrum element.
